UNITED STATES PATENT OFFICE.

JAMES H. O'NEILL AND MORRIES T. COLEMAN, OF MACEDON, NEW YORK.

LATCH MECHANISM.

1,063,466.

Specification of Letters Patent.

Patented June 3, 1913.

Application filed August 8, 1912. Serial No. 714,082.

To all whom it may concern:

Be it known that we, JAMES H. O'NEILL and MORRIES T. COLEMAN, citizens of the United States, and residents of Macedon, in 5 the county of Wayne and State of New York, have invented certain new and useful Improvements in Latch Mechanism, of which the following is a specification.

This invention relates to latch-mechanism for use in connection with drop-bottom buckets or similar devices, such as are employed for conveying concrete and various materials.

The general object of the invention is to 15 produce a mechanism which shall be simple and durable in construction and convenient in operation.

A more particular object of the invention is to produce a latch-mechanism which will 20 always act positively and certainly to engage, and hold closed, the bottom of the bucket. To this end we employ a latch of such form and construction that it is adapted to swing upwardly against the bottom of 25 the bucket, so as to force the bottom toward closed position, and with this latch we employ positively-acting manually-operable means for so swinging it.

Other objects of the invention, and the 30 features of construction by which they are attained, will be set forth in connection with the following description of the preferred embodiment of the invention.

In the accompanying drawing: Figure 35 1 is a front-elevation of a bucket provided with latch-mechanism embodying the present invention, the bottom of the bucket being released and partly open; Fig. 2 is a front-elevation showing the bottom held in 40 closed position by the latch-mechanism; and Fig. 3 is a side elevation, partly in section, with the mechanism in the same position as in Fig. 2.

The invention is illustrated as applied to 45 a drop-bottom bucket of which the general form is familiar, this bucket comprising a sheet-metal body 5, rectangular in horizontal section, and a flat bottom 6 which normally closes the lower end of the body. The 50 bottom 6 is carried by arms 7 pivoted, at 8, to one side of the body, so that the bottom is hinged to the body and may swing downwardly to open the bucket and discharge its contents.

55 The bottom is normally held in closed position by means of a latch having two fin-

gers 9 which press upwardly against the margin 10 of the bottom, as shown in Figs. 2 and 3. This latch is an integral member comprising, in addition to the fingers 9, 60 trunnions 11 at its ends which have bearings in eyes formed upon straps 12 riveted to the side of the body, and a central crank-portion 13 connecting the trunnions.

The latch is actuated by manually-operable mechanism in the form of a toggle. 65 This mechanism comprises a link 15 pivoted, at its lower end, to the crank 13 by means of a strap 14 inclosing the crank. The strap is sufficiently loose upon the crank to permit a slight lateral angular movement of the link in addition to its pivotal movement. The upper end of the link is pivoted, by means of a bolt 17, to a hand-lever 16 which, in turn, is pivoted upon a stud 70 18 supported by a lug 19 on the side of the bucket. The short portion of the hand-lever, between the pivots 17 and 18, is of such length that it acts with the link 15 as a toggle-lever. When the bottom of the bucket is 75 completely closed, and the fingers 9 of the latch are swung upwardly against the bottom, the toggle occupies the position shown in Fig. 2, in which the pivots are sufficiently beyond the straight-line position to lock the 80 latch in closed position. When the bucket is to be opened it is necessary merely to swing the hand-lever upwardly, raising the crank 13 and lowering the fingers 9 out of engagement with the bottom, whereupon the 85 bottom may swing open by the action of gravity. In closing the bucket again the hand-lever is held in raised position, thus holding the fingers out of the path of the bottom 6 during the closing movement of 90 the latter, and, after the bottom has been swung upwardly to, or approximately to, closed position the hand-lever is again depressed. By this last action the fingers 9 are forced inwardly and upwardly and into 95 engagement with the margin 10 of the bottom. It should be noted that this engagement occurs regardless of the fact that the bottom may not have been already returned completely to closed position against the 100 lower edge of the body of the bucket, and that by the continued downward movement of the hand-lever and upward movement of the fingers the bottom, after such engagement, may be forced positively upward. Accordingly, if any slight obstruction to the 105 full closing of the bottom exists, the posi-

tive action of the latch may still force the bottom to closed position. In case such complete closing is prevented by an unyielding obstruction, such as a small stone, the latch 5 may still operate to hold the bottom in its raised position owing to the fact that the toggle has a powerful effect upon the latch even before it reaches straight-line position, and thus the weight of the hand-lever, acting upon the toggle, will hold the bottom with sufficient security for practical purposes even when it is prevented from absolutely closing.

By pivoting the hand-lever to swing in a plane close to, and substantially parallel with, the side of the bucket it is rendered unnecessary for the hand-lever to be swung outwardly and away from the side of the bucket, so that the hand-lever need not project to any great distance from the bucket in any operative position. This is a feature of great value where the bucket is employed for the conveyance of concrete, since it enables the bucket to be properly discharged 25 and operated in a mold affording little space beyond that necessary for the reception of the bucket.

We claim:—

1. In a drop-bottom bucket with a hinged bottom, latch-mechanism for holding the bottom closed, said mechanism comprising a latch movably mounted on the body of the bucket and adapted to engage the bottom with an upward movement, a hand-lever 35 pivoted upon the body and arranged to swing in a plane substantially parallel with and close to a side of the body, and a link connecting the latch and the hand-lever and constituting, with the latter, a toggle where- 40 by the latch may be forced positively into engagement with the bottom.

2. In a drop-bottom bucket with a hinged bottom, latch-mechanism for holding the bottom closed, said mechanism comprising a

latch pivoted on the body of the bucket outside of the bottom and adapted to swing upwardly against the bottom so as to force the latter toward closed position, and manually-operable mechanism acting positively to swing the latch upwardly. 45

3. In a drop-bottom bucket with a hinged bottom, latch-mechanism for holding the bottom closed, said mechanism comprising a latch pivoted on the body of the bucket outside of the bottom and adapted to swing upwardly against the bottom so as to force the latter toward closed position, and toggle-mechanism for actuating the latch positively in said direction, said mechanism including a manually-operable lever pivoted upon the body to swing in a plane substantially parallel with a side of the body. 50

4. In a drop-bottom bucket with a hinged bottom, latch-mechanism for holding the bottom closed, said mechanism comprising a latch carried by the body and movable out of and into engagement with the bottom in a direction to force the bottom toward closed position, and manually-operable mechanism for actuating the latch positively in said direction. 55

5. In a drop-bottom bucket with a hinged bottom, latch-mechanism for holding the bottom closed, said mechanism comprising a latch pivoted on the body of the bucket near the lower edge thereof and having a part adapted to swing upwardly into engagement with the bottom and to force the bottom toward closed position, and toggle-mechanism and a hand-lever for actuating the latch, the hand-lever normally acting, through its weight, to force the latch toward its upper position. 60
